UNITED STATES PATENT OFFICE.

WILLIAM BORNKESSEL, OF RIDGEFIELD PARK, NEW JERSEY.

DESIGN FOR A FINGER RING.

Application filed August 14, 1926. Serial No. 18,749. Term of patent 3½ years.

To all whom it may concern:

Be it known that I, WILLIAM BORNKESSEL, a citizen of the United States of America, and resident of Ridgefield Park, county of Bergen, and State of New Jersey, have invented a new, original, and ornamental Design for Finger Ring, of which the following is a specification, reference being had to the accompanying drawing, forming part thereof.

In the drawing, the figure is a perspective view of a finger ring showing my new design.

I claim:

The ornamental design for a finger ring, as shown.

WILLIAM BORNKESSEL.
